Attorneys

UNITED STATES PATENT OFFICE.

GEORGE JACKSON, OF NEW HAVEN, CONNECTICUT.

BUILDING CONSTRUCTION.

Application filed September 12, 1919. Serial No. 323,283.

To all whom it may concern:

Be it known that I, GEORGE JACKSON, a citizen of the United States, residing at New Haven, in the county of New Haven and 5 State of Connecticut, have invented certain new and useful Improvements in Building Construction, of which the following is a specification.

This invention relates to an improved column for building construction.

A further object of the invention is to provide in a building construction, standard parts such as columns, which are constructed of pressed steel, punched and bent at a 15 factory, and which are comparatively light in weight, consequently easily transported, and which can be erected with relative ease, resulting in the saving of expensive labor, such as the riveting and erecting of the improved type of steel I beams or columns now commonly employed for this purpose; and also to provide means whereby the column sections may be quickly and easily connected and enclosed in casing blocks of suitable fire-proof material; the said fire-proofing blocks coating with the columns, for 20 providing forms into which cementitious material such as concrete, or the like, is poured and allowed to harden to complete 25 the frame work of the building construction, thereby eliminating the relatively expensive lumber parts commonly used, and the resulting waste of material.

Other objects of the invention will appear 35 in the following detailed description taken in connection with the accompanying drawings, forming a part of this specification, and in which drawings:

Figure 1 is a fragmentary view partly in 40 section through a building constructed in accordance with this invention.

Figure 2 is a cross-section taken on the line 5—5 of Figure 1 through one of the column foundations of the building construction.

Figure 3 is a cross section through a column of the building construction.

Figure 4 is a detail perspective of a retaining plate employed in the building construction.

Figure 5 is a fragmentary perspective of one of the column structures.

Figure 6 is a detail perspective of a coupler employed in the column structure.

Figure 7 is a perspective view of a stamped

plate or sheet, of which the column is formed, prior to the bending thereof.

Figure 8 is a top plan of one of the standard sections of the column.

Figure 9 is a perspective view of a brace 60 member used in the column structure.

Referring more particularly to the drawings, wherein like characters indicate like and corresponding parts throughout the several views, the columns 20 of the building construction are formed of a plurality 65

of the column sections 21 which are formed of sheet steel pressed so as to provide a relatively light structure embodying sufficient strength and rigidity to properly re-inforce 70

the concrete construction of the building and still provide a device which may be easily transported, and also easily erected. These column sections 21 are formed of 75

flat sheets of metal as indicated in Figure 7 of the drawings, and when in a flat state are punched to provide the spaced cut-out portions 22 which decrease the weight of 80

the columns, and the laterally extending ears 23, which facilitate the attachment of 85

one section to the adjacent section in a column structure. These ears 23 are split longitudinally or laterally of the length of 90

the column section 21, and the portion 24 intermediate the splits are bent outwardly and inwardly alternately as shown in Figure 5 95

of the drawings, to provide straps for receiving therebeneath the substantially U-shaped coupling members 25, employed for 100

connecting the various column sections 21 at spaced intervals, in rigidly connected upright position prior to the placing of the fire-proof enclosing blocks or bricks. Up- 105

standing ears 27 are formed upon the upper end of the column sections 21 and 110

they are bent to extend inwardly and horizontally, being provided with perforations 28. In one of the column sections 21, the column rod 29 extends through the opening 28 in the horizontal portion thereof, and where a plurality of the column sections 21 are placed in superposed position, as shown in Figure 1 of the drawings, the column rod 29 extends through the opening 105

in plan. This base plate 32 and pipe 30 are embedded in a foundation block 31. The foundation block 31 is composed of a plurality of blocks 33 of any approved fire-proofing material, which are connected at their ends by means of the connecting or coupling pins 34, and intermediate their ends by the brace rods or stays 35, the ends of which are anchored in suitable recesses 36, formed in the block 33 and illustrated in Figure 1 of the drawings. In case it is necessary to splice the column rod 29, a joint or coupling 37, shown in Figure 6 of the drawings is employed to connect the meeting ends of two sections of the rod 29. This coupling 37 is formed of flat sheets of bar metal and has its ends bent at right angles thereto, it also has a plurality of ears 38 cut therefrom, and bent at right angles to the main body of the joint or coupling plate 37, and parallel to the angled ends 39 thereof. The angled ends 39 and the upper and lowermost ears 38 are provided with openings 40 which receive the rod sections therethrough, while the ends of the upper and lower rod sections engage the intermediate ear 38. Thus the coupling member 37 will connect the rods and maintain them in their connected vertical position until the cementitious material is poured into the column, and hardened.

The horizontally bent ears 27 of the side column sections 21 are provided or utilized to facilitate the connecting of cross or floor beams, to the column structure 20, and spurred pins 41 are inserted through the openings 28 in these angled ears 27 and to engage the girder sections 43. The sections 21 are substantially U-shaped in cross section as illustrated in Figures 3 and 8 of the drawings, and they have the corners at the junction of their bight portions and legs bent outwardly and rolled as shown at 44, to receive therein the rolled ends 45 of the bracing members 46. The bracing members 46 are substantially V-shaped in plan, and their ends 45 are rolled to snugly fit within the rolled corners of the sections 21 or 43, and the apex of the couplings are rolled as shown at 48 to fit about the vertical column rod 29, or other analogous bracing rod in the building construction. These brace members 46 are preferably formed of spring steel so as to provide sufficient frictional engagement between the rolled end 45, and the rolled corner 45 to maintain them in position, and to cause them to assist in supporting the vertical column rods 29 in their proper positions during the constructing of the building structure.

In forming a column 20 of the building construction, a plurality of the substantially U-shaped column sections 21 are con-

nected by means of the U-shaped couplings 25, in the manner illustrated in Figure 3 of the drawings, to provide the desired shape of column. In case the legs of certain of the column sections 21 do not reach, to permit their direct connection, suitable plates as indicated at 50 may be provided for connecting these end portions, as clearly shown in Figure 3 of the drawings, to form a skeleton frame for the column. Blocks 51 of fire-proof material are then placed about the skeleton column formed by the substantially U-shaped section 21. These various blocks 51 are made, from the specifications of the building construction so as to fit about the outer surface of the column skeleton and certain of the blocks are provided with substantially circular recesses, as indicated at 52, which receive therein the circular corner portions 44, of the column sections 21. The blocks 51 are connected by suitable connecting means as indicated at 53, and when they are placed about the column they provide a form, into which the cementitious material, such as concrete or the like indicated at 54, may be poured for forming the complete column structure, and thereby eliminating the necessity of using wood forms or patterns to form the column structures, as is generally resorted to in present approved methods of concrete building structures. In bracing the column rod 29 within the skeleton column structure prior to the filling of this column structure with cementitious material, spring braces 55 substantially V-shaped are employed, and these braces have their end portions rolled inwardly, as shown at 56, in contradistinction to the outward rolling of the ends of the braces 46. The apexes of these substantially V-shaped braces 55 are rounded as shown at 57, to engage about the column rod 29.

Changes in details may be made without departing from the spirit of this invention, but;

I claim:

1. In a column, the combination of a sheet metal casing having openings in the side thereof, means formed on the casing and projecting outwardly from the sides thereof, fire proof blocks disposed entirely about said metal casing and engaging said last mentioned means to space the same from the sides of said casing, and cementitious material disposed within said casing, through the openings therein, and intermediate the interior of said blocks and the exterior of the sides of said casing, to provide a column structure.

2. A column comprising in combination a plurality of substantially U-shaped sheet metal forms having openings in the side thereof, means connecting said U-shaped form in parallel relation to provide a casing, certain portions of each of said U-shaped

- members having extensions thereon projecting from the sides thereof, fireproof blocks engaging said extension to be held in spaced relation with respect to the sides of said 5 casing, and cementitious material within said casing through the openings therein, and engaging in the space intermediate the fire blocks and the sides of said casing to provide a column.
- 10 3. In building construction, the combination of columns comprising a plurality of uniform sheet-metal sections substantially U-shaped in cross section, ears formed upon said sections at spaced intervals and being 15 split, the portions of the ears intermediate said splits being bent outwardly at opposite directions to form straps, coupling straps for insertion beneath the straps formed in said ears to connect the sections in longitudinally abutting relation to provide a 20 column formation, ears formed upon the ends of said sections and bent at right angles to the length of the sections, said last named ears provided with perforations, and a spacing rod extending longitudinally through the center of the column and extending 25 through the opening in the horizontal ear carried at the end of one of the sheet metal sections.
- 30 4. In building construction, the combination of columns comprising a plurality of uniform sheet-metal sections substantially U-shaped in cross section, ears formed upon said sections at spaced intervals and being 35 split, the portions of the ears intermediate said splits being bent outwardly at opposite directions to form straps, coupling straps for insertion beneath the straps formed in said ears to connect the sections in column 40 formation, ears formed upon the ends of said sections and bent at right angles to the length of the section, said last named ears provided with perforations, a spacing rod extending longitudinally through the 45 center of the column and extending through the opening in the horizontal ear carried at the end of one of the sheet metal sections, and substantially V-shaped spring braces 50 embracing said rod and having their end portions shaped for snugly fitting the section.
5. In building construction, the combination of columns comprising a plurality of uniform sheet-metal sections, substantially 55 U-shaped in cross section, said sections being rounded at their corners to provide portions projecting outwardly of the faces of the sections, ears formed upon the ends of said sections and bent transversely to the length 60 of the sections, a supporting rod extending longitudinally through the column and projecting through one of said transversely bent ears.
6. In building construction, the combination 65 of columns comprising a plurality of
- uniform sheet-metal sections substantially U-shaped in cross section, said sections being rounded at their corners to provide portions projecting outwardly of the faces of the sections, ears formed upon the ends of said sections and bent transversely to the length 70 of the sections, a supporting rod extending longitudinally through the column and projecting through one of said transversely bent ears, and substantially V-shaped spring braces embracing said rod and having their ends rounded for snug fitting in the rounded corners of the sections.
7. In building construction, the combination 75 of columns comprising a plurality of uniform sheet metal sections substantially U-shaped in cross section, means connecting said sections in column formation, a central reinforcing rod disposed longitudinally within said column sections, and tie braces 80 connecting said rod to the U-shaped column sections.
8. In building construction, the combination 85 of a column shell, a central reinforcing rod, and a V-shaped spring brace, the apex of said brace being formed to embrace the reinforcing rod, and the ends thereof rounded for engagement with the column shell for maintaining the reinforcing rod and column shell in fixed relation.
9. In building construction, the combination 90 of columns comprising a plurality of uniform sheet metal sections substantially U-shaped in cross section, means connecting said sections in column formation, said sections being rounded at their corners to provide internally hollowed recesses, a central reinforcing rod disposed longitudinally within said column section, and a V-shaped 95 spring brace, the apex of said brace being formed to embrace the reinforcing rod and the ends thereof rounded for engagement in the recessed portion of the rounded sections for maintaining the column shell and the reinforcing rod in fixed relation.
10. In building construction, the combination 100 of a column comprising a plurality of sheet metal sections, a central reinforcing rod, means connecting said sections and said rod, a base plate upon which said centrally reinforcing rod rests, a hollow tubular section engaging said base plate, and having said reinforcing rod disposed therein, and cementitious material surrounding said base plate, tubular section, and sheet metal sections for forming the complete columns.
11. A column comprising a plurality of 105 U-shaped ribbed metal sections, means connecting the sections together in stable relation, fire blocks entirely disposed about said sections, and cementitious material disposed intermediate said sections and said fire blocks.
12. A column construction comprising a 110 plurality of sheet metal sections substan-

tially U-shaped in cross section, means connecting said sections at their free longitudinal edges to provide an enclosed structure, said sections having rounded portions at the 5 corners thereof which extend laterally of the sides of the sections.

13. As an article of manufacture, a building construction support member of sheet metal bent substantially U-shaped in cross 10 section, providing sides and a portion connecting said sides, the junctures of the sides and the portion connecting said sides being rounded as to extend laterally of the planes of said portion and said sides.

14. As a new article of manufacture, a sheet metal support member having a plurality of openings therein bent substantially U-shaped to provide parallel side portions and a connecting portion, the longitudinal corners of the junctures of said side portions 15 with the connecting portion being rounded as to extend outwardly of the planes of the connecting portion and sides, said side portions having attaching ears extending outwardly of the free longitudinal edges thereof. 20 25

GEORGE JACKSON.
